(57) **CLAIM**

The ornamental design for a spring-loaded closure lid for a hazardous waste container, as shown and described.

DESCRIPTION

FIG. 1 is an upper perspective view of a spring-loaded closure lid for a hazardous waste container, showing my design;

FIG. 2 is a right side elevation view thereof;

FIG. 3 is a left side elevation view thereof;

FIG. 4 is a front end elevation view thereof;

FIG. 5 is a rear end elevation view thereof;

FIG. 6 is a top plan view thereof; and,

FIG. 7 is a bottom plan view thereof.

The broken line showing of a container in FIG. 3 is included for the purpose of illustrating environmental structure and forms no part of the claimed design.
